UNITED STATES PATENT OFFICE.

GABRIEL J. KEY, OF ARARAT, NORTH CAROLINA.

DESIGN FOR A HORSESHOE-RACK.

48,940.

Specification for Design.

Patented Apr. 25, 1916.

Application filed November 20, 1915. Serial No. 62,660. Term of patent 14 years.

To all whom it may concern:

Be it known that I, GABRIEL J. KEY, a citizen of the United States, residing at Ararat, in the county of Surry and State of North Carolina, have invented a new, original, and ornamental Design for Horseshoe-Racks, of which the following is a specification, reference being had to the accompanying drawing, forming a part thereof.

Figure 1 is a front view; Fig. 2 is a side

view; and Fig. 3 is a top plan view of a horse shoe rack, showing my new design.

I claim:

The ornamental design for a horse shoe rack, as shown.

GABRIEL J. KEY.
